[57] **CLAIM**

The ornamental design for a kickstand support pad, as shown and described.

DESCRIPTION

FIG. 1 is a top plan view of the kickstand support pad, showing my new design;

FIG. 2 is a rear elevation view thereof;

FIG. 3 is a bottom plan view thereof;

FIG. 4 is a right side elevational view thereof, the left side being a mirror image of that shown;

FIG. 5 is a front elevation view thereof; and,

FIG. 6 is a rear perspective view thereof with the kickstand shown in broken lines and not forming part of my new and ornamental design.
